Primary Examiner — Nathan M Johnston(74) *Attorney, Agent, or Firm* — Hudak, Shunk & Farine Co. LPA(57) **CLAIM**

The ornamental design for a dual post retaining member, as shown and described.

DESCRIPTION

FIG. 1 is a front elevational view of a dual post retaining member showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a slightly downward-looking perspective view thereof; and,

FIG. 8 is a slightly upward-looking perspective view thereof.
